UNITED STATES PATENT OFFICE

170,533

HOLDER FOR FIRE EXTINGUISHER
GRENADECadwell C. Irwin, Littleton, Colo., assignor to Red
Comet, Incorporated, Littleton, Colo., a corpo-
ration of Colorado

Application January 19, 1953, Serial No. 23,188

Term of patent 14 years

(Cl. D16—2)

To all whom it may concern:

Be it known that I, Cadwell C. Irwin, a citizen of the United States, residing in Littleton, State of Colorado, have invented a new, original, and ornamental Design for a Holder for Fire Extinguisher Grenade, of which the following is a specification, reference being had to the accompanying drawing, forming a part hereof.

Fig. 1 is a front elevational view of a holder for fire extinguisher grenade embodying my new design.

Fig. 2 is a side elevational view of the same.

Fig. 3 is a top plan view thereof.

I claim:

The ornamental design for a holder for fire extinguisher grenade, as shown.

CADWELL C. IRWIN.
